UNITED STATES PATENT OFFICE.

HARRY A. LEONARD, OF HOPEDALE, MASSACHUSETTS, ASSIGNOR TO DRAPER CORPORATION, OF HOPEDALE, MASSACHUSETTS, A CORPORATION OF MAINE.

BUILDER MECHANISM FOR SPINNING OR WINDING MACHINES.

Application filed February 9, 1926. Serial No. 87,052.

This invention relates to machines for winding yarn on bobbins or receivers and is more particularly directed to the means for laying preliminary windings or a 5 "bunch" upon the bobbins or receivers at the commencement of the windings.

In looms of the feeler type, which are now extensively used, it is the practice to replenish the filling prior to complete exhaustion of that in the shuttle, and such replenishment may be effected either by substituting other filling in the shuttle or by changing the shuttle itself. In order that perfect cloth may be woven, however, it is 10 necessary that the final pick prior to replenishment shall be a "full pick", that is, that a full length of filling be laid throughout the length of the shed, and to this end it has been usual to cause the feeler mechanism in 15 the loom to call for a change of filling when there is sufficient yarn or filling in the shuttle to provide a full final pick.

An important feature of the present invention, therefore, consists of means for 20 providing the filling carriers or bobbins with a reserve supply of filling, sufficient in amount to insure a final perfect pick, and to wind the reserve supply upon the filling carriers or bobbins without substantial traverse, 25 and upon the finish of such preliminary windings to resume service traverse.

A machine operating on this general principle is shown and described in the patent to Harry A. Leonard, No. 1,412,808, dated 30 April 11, 1922, and the machine of the patent has been practical and successful. Where, 35 however, the preliminary windings are dependent upon a manual operation by the machine attendant after the machine has been supplied with a fresh set of bobbins, it may happen at times that the machine attendant will fail to manipulate the manual controlling device and start the machine with full service traverse, the result being 40 that no preliminary windings or "bunch" will be placed upon the yarn receivers or bobbins.

An important feature of the invention 45 therefore consists in means for preventing the machine from being started by the attendant until the controlling means for forming the preliminary windings or "bunch" has been manipulated, thereby insuring that upon starting the machine, a series of preliminary windings or a "bunch" will be

placed upon the bobbins or receivers prior to the commencement of regular service traverse.

The invention and novel features and new combination of parts will best be made clear 60 from the following description and the accompanying drawings of one good form thereof.

In the drawings:—

Fig. 1 is a front view of a woolen or 65 worsted spinning frame containing the present invention, some of the parts being broken away for clearness of illustration;

Fig. 2 is an end view of the same machine provided with the present invention; and 70

Fig. 3 is an enlarged detail view, partly in section, showing one good form of means for suspending the operation of the traversing mechanism during preliminary windings, and upon the completion thereof 75 to automatically resume service traverse.

The invention is herein shown and described in connection with a woolen or worsted spinning frame, but it is to be understood that it is not necessarily limited 80 thereto but may be employed in other spinning or winding machines.

The machine frame may be of usual construction and as herein shown comprises the end frames 1, only one of which is shown, 85 which are connected by the cross-girths 2 above which is the rail 3 on which the yarn receivers or bobbins 4 may be mounted, and such rail may be given a traversing movement relative to the caps 5 for guiding the 90 yarn to the yarn receivers.

Extending downwardly from the rail 3 are the lifting rods 6 which are connected at their lower ends to a chain 7 associated with a longitudinally movable rail 8 which has 95 imparted thereto longitudinal movements, as usual in this class of machines.

The traversing movement is imparted to the longitudinally movable rail 8 by means of a traversing mechanism. In the present 100 instance of the invention, the traversing mechanism comprises the swinging arm 9 pivotally supported upon the machine frame at 10 and having a roller 11 which bears upon the builder cam 12, and riding upon 105 the flat face 13 of the swinging arm 9 is a roller 14 connected to the traversing screw 15 to impart thereto and to the longitudinally movable rail 8 the desired traversing movement for the yarn guiding means. The 110

mechanism so far described is not new and is now well understood in the art, so that further description thereof is unnecessary.

The builder cam 12 is mounted upon the 5 cam shaft 16 and rotates therewith under the influence of the cam shaft operating means. Such operating means as shown comprises the belt pulley 17 which may be driven from any suitable source of power, 10 and has connected therewith the gear 18 meshing with the gear 19, on the hub portion of which is a worm 20. Loosely mounted on the cam shaft 16 is a worm wheel 21 which is preferably placed upon 15 the cam shaft adjacent one of the shaft bearings 22, and such worm wheel is engaged with the worm 20, the construction being such that upon operation of the pulley 17 the worm wheel 21 will be rotated.

20 The hub portion 23 of the worm wheel 21, Fig. 3, is provided with a clutch member adapted at times to be operatively connected to an associated clutch member which is mounted upon the cam shaft for rotative movement therewith. In the present instance, the hub portion 23 of the worm wheel 21 is provided with a pin 24 which is adapted to engage with a recess or opening 25 in a clutch member 26 mounted upon 25 a hub portion 27 of a collar 28 secured to the cam shaft 16 by a pin or set screw 29, and the clutch member 26 is normally under the influence of a spring 30 interposed between it and the collar 28, the construction 30 being such that when the pin 24 and opening 25 are in alignment, they will be engaged under the influence of the spring 30. The clutch member 26 is splined to the hub portion 27 of the collar 28 by a key 31, 35 so that while the clutch member 26 is movable towards and from the hub portion 23 of the worm wheel, it nevertheless rotates with or imparts rotative movement to the cam shaft 16.

40 The clutch member 26 has a circular groove 32 in which is engaged the pins 33 carried by a yoke member 34 pivotally mounted at 35 to a bracket 36 secured to the side frame 1 of the machine, and extending 45 upwardly and outwardly from the pivotal mounting 35 of the yoke is a hand-piece 37 which may be manually operated to disengage the clutch members, thereby permitting the cam shaft 16 to remain at rest.

50 When a set of bobbins or carriers has been fully wound, it is the usual practice to lower the rail 3 for doffing and permit a new set of bobbins or yarn carriers to be placed upon the spindles. In the operation 55 of applicant's invention, and before commencing to wind a fresh set of bobbins, the machine attendant manually operates the hand-piece or lever 37 thereby moving the clutch member 26 longitudinally of the shaft 16, thus disengaging the clutch mem- 60 bers, which normally are operatively engaged during main traverse wind. At this time the roller 11 bears slightly at one side of the nose 38 of the traverse cam 12, and under the stress of the weight pressing 65 against the swinging arm 9 the traverse cam 12 is given a slight rotative movement which is imparted to the cam shaft 16, thereby carrying the end of the pin 24, which has been disengaged from the opening 25 in the clutch member 26, to one side of said opening 25, so that the end of the pin rests upon the adjacent plane face of the clutch member 26, and the traversing cam 12 is thus disconnected from the driving means including the worm wheel 21, and remains at rest when the machine is started. Should the machine attendant, however, fail to manipulate the hand piece 37 before he starts 70 the machine, the traversing cam will remain in action and regular traverse will be commenced at once, so that no preliminary windings or "bunch" will be placed upon the filling carriers or bobbins.

75 It is one of the purposes of the present invention to require the machine attendant to manipulate the hand piece 37 and thus disconnect the traverse cam from its operating means before he can start the machine, so that all danger of winding filling carriers or bobbins without "bunches" is avoided.

80 Machines of the general type herein shown are usually provided at the upper part of the side member 1 of the machine 85 with a machine starting mechanism, and the present invention provides a lock associated with the hand piece 37 so that the machine attendant cannot manipulate the starting rod or starting mechanism to start the machine without first manipulating the hand piece 37 to disconnect the traverse cam from its driving means.

85 Mounted upon the side frame 1, preferably at the upper part thereof, is a bracket 90 having a foot portion 40 to which is secured a bracket or supporting member 41 by means such as a bolt 42. Extending through the riser 43 of the bracket 41 and the bracket 39 is a starting member 44 confined from longitudinal movement by a collar 45, and the starting member 44 is provided with a hand wheel 46, so that it may be turned without longitudinal movement. The inner end portion of the starting member 44 is supported by a bracket 47 secured to the bracket 41, as indicated in Fig. 1, and between the brackets 39 and 47 the starting member 44 is provided with a screw thread 48 which engages a corresponding screw thread in a starting slide 49 to which is connected the starting rod 50, the construction being such that should the slide 49 be moved to the left, Fig. 1, it will correspondingly move the starting rod 50 and cause 95

130

the machine to operate, it is being understood that the starting rod 50 is associated with either a belt shifter or a clutch mechanism, as usual, for throwing power onto the machine.

5 The bracket 41 is provided with a slot 51, and pivotally supported upon the bracket at 52 is a lock 53 which may be variously contrived, but is herein shown as a bell crank lever. The lock 53 is normally under the influence of a spring 54 for throwing the lock 53 into its locking position, as indicated in Fig. 1, a position it will assume automatically when the machine is stopped.

10 15 This relation of parts is indicated in Fig. 1. Connected to the downwardly extending arm 55 of the lock is a chain or flexible connection 56 leading to the hand piece 37. In the present instance of the invention, the 20 flexible connection 56 passes over a guide pulley 57 at the top of the end frame, and then over a guide pulley 58 adjacent the hand piece 37, and from there the flexible connection leads to the hand piece where it 25 is secured thereto at 59. The guide pulley 58 may be conveniently secured to the end frame 1, as at 60.

After the machine has been stopped and the bobbins or carriers doffed, as usual, and 30 it is desired to start the machine with a fresh set of filling carriers or bobbins to first wind the "bunch" or preliminary windings, the machine attendant must first manipulate the hand piece 37 to disconnect the 35 traverse cam 12 from its operating means, thereby tripping the lock 53 from in front of the slide 49 so that the latter may then be moved to the left, Fig. 1, to start the machine. Should the machine attendant fail 40 to manipulate the hand piece 37, he cannot start the machine because of the lock 53 which must be disengaged from its locking position, as indicated in Fig. 1, and such disengaged position is reached by manipulation 45 of the hand piece 37 which insures that upon starting the machine the bobbins or carriers will first be supplied with preliminary windings of substantially no traverse. During the formation of the reserve 50 supply or preliminary winding, the end of the pin 24 rides over the face of the clutch member 26 and upon the completion of such preliminary windings when the pin 24 has again assumed the position opposite the opening 55 25 of the clutch member 26, the the spring 30 will automatically engage the clutch members, whereupon the traverse cam 12 will be operated to lay the windings upon the bobbins or carriers with a service 60 traverse. The machine is thus rendered "fool proof" to the extent that it cannot be started to wind the yarn upon the filling carriers or bobbins without first disengaging 65 the clutch members to permit the traverse cam to remain at rest and effect pre-

liminary windings upon the filling carriers or bobbins.

What is claimed is:—

1. In a yarn winding or spinning machine, the combination of yarn guides for 70 directing yarn to yarn receivers, a traversing mechanism for imparting a traverse movement to the yarn guides, a device suspending the operation of the traversing mechanism to wind yarn upon the yarn receivers without substantial traverse, machine starting mechanism, and connections between the starting mechanism and suspending device to prevent starting the machine until the suspending device has been 75 actuated.

2. In a yarn winding or spinning machine, the combination of yarn guiding means for directing yarn to yarn receivers, a traversing mechanism for imparting a 85 traverse movement to the yarn guiding devices, means for suspending the operation of the traversing mechanism to wind yarn upon the yarn receivers without substantial traverse, means for automatically reinstating the operation of the traversing mechanism upon completion of the winding of yarn 90 without traverse, machine starting mechanism, and connections between the starting mechanism and suspending devices to prevent starting the machine until the suspending means has been 95 actuated.

3. In a yarn winding and spinning machine, the combination of yarn guiding means, traversing mechanism therefor, machine starting means, a manually operated device for suspending the operation of the traversing mechanism to lay preliminary winding upon yarn receivers without traverse, and a locking device for the starting means to lock it from movement to starting position, connected to the manually operated device to prevent starting the machine until the manually operated device has been 100 moved to suspend the action of the traversing mechanism.

4. In a yarn winding and spinning machine, the combination of yarn guiding means, traversing mechanism therefor, machine starting means, a manually operated device for suspending the operation of the traversing mechanism to lay preliminary winding upon yarn receivers without traverse, a locking device for the starting means connected to the manually operated device 115 to prevent starting the machine until the manually operated device has been moved to suspend the action of the traversing mechanism, and means acting automatically to reinstate the operation of the traversing mechanism upon completion of the winding of yarn without traverse.

5. In a machine of the character described, the combination of yarn guides, traversing mechanism therefor, a manually 130

operated throw out device for rendering the traversing mechanism inoperative before starting the machine to lay preliminary winding on yarn receivers, starting mechanisms for the machine, a lock for locking the starting mechanism in stop position, and connections between the lock and said throw out device to prevent starting the machine until after said throw out device has been operated to render the traversing mechanism inoperative.

6. In a machine of the character described, the combination of yarn guides, traversing mechanism therefor, a throw out device for rendering the traversing mechanism inoperative before starting the machine to lay preliminary winding on yarn receivers, starting mechanism for the machine, a lock for the starting mechanism, to prevent movement thereof to starting position, connections between the lock and said throw out device to prevent starting the machine until after said throw out device has been operated to render the traversing mechanism inoperative, and means for automatically rendering the traversing mechanism operative on completion of the preliminary windings.

7. In a machine of the character described, the combination of yarn receivers, yarn guides for directing yarn to the yarn receivers, a builder arm, a builder cam, means for rotating the builder cam to effect traverse of the yarn guides, a manually operated device for suspending operation of the builder cam to wind a reserve supply of yarn on the yarn receivers without traverse when the machine is started, starting mechanism for the machine, and a lock for locking the starting mechanism from movement to starting position connected to the said manually operated device to prevent starting the machine until after the cam is disconnected from its operating means.

8. In a machine of the character described, the combination of yarn guides, a builder arm, a builder cam, a cam shaft carrying said cam, clutch members for connecting the cam shaft to its operating means, a manually controlled arm for disengaging the clutch members, starting means for the machine, a lock to prevent

starting the machine, and a trip for the lock connected to the manually controlled arm to permit the machine to be started only after 55 manual disengagement of the clutch members.

9. In a machine of the character described, the combination of yarn guides, a builder arm, a builder cam, a cam shaft 60 carrying said cam, clutch members for connecting the cam shaft to its operating means, a manually controlled arm for disengaging the clutch members, starting means for the machine, a lock to prevent 65 starting the machine, a trip for the lock connected to the manually controlled arm to permit the machine to be started only after manual disengagement of the clutch members, and means for reengaging the clutch 70 members to operate the cam after one revolution of one of the clutch members.

10. In a builder mechanism, the combination of a builder arm, a cam for actuating the arm, a cam shaft carrying the cam, 75 a worm wheel loose on the cam shaft and having a clutch member, a second clutch member rotatable with the cam shaft and movable longitudinally thereof, manual means for disengaging the clutch members, 80 starting mechanism for the machine, means for locking the starting mechanism, and connections between the locking means and said manual means for tripping the lock by operation of the manual means.

11. In a builder mechanism, the combination of a builder arm, a cam for actuating the arm, a cam shaft carrying the cam, a worm wheel loose on the cam shaft and having a clutch member, a second clutch 90 member rotatable with the cam shaft and movable longitudinally thereof, manual means for disengaging the clutch members, starting mechanism for the machine, means for locking the starting mechanism, connections between the locking means and said 95 manual means for tripping the lock by operation of the manual means, and means for automatically reengaging the clutch members after a predetermined relative movement thereof.

In testimony whereof, I have signed my name to this specification.

HARRY A. LEONARD.
